UNITED STATES PATENT OFFICE.

ROBERT D. PIKE, OF SAN FRANCISCO, CALIFORNIA.

CALCINING APPARATUS.

Application filed December 20, 1922. Serial No. 608,088.

To all whom it may concern:

Be it known that I, ROBERT D. PIKE, a citizen of the United States, residing in city and county of San Francisco and State 5 of California, have invented certain new and useful Improvements in Calcining Apparatus, of which the following is a specification.

The hereinafter described invention relates to a calciner of the multiple hearth type, designed more particularly for adaptation to the economic calcination of carbonate rocks, such as magnesite, and calcite, and the invention is more specifically adapted 10 to the requirements of the apparatus for calcining and clinkering of carbonaceous rocks set forth and described in my pending application, Serial No. 572,895, filed in the United States Patent Office under 15 date of July 25th, 1922, for an apparatus for calcining and clinkering, and in which apparatus the hot calcined material is immediately passed through a rotary kiln for clinkering, thence transferred into and 20 passed through a cooler, the larger portion of the hot air from the cooler being delivered to the calciner for combustion of the fuel therein, while the smaller portion of the hot air from the cooler passes to the rotary kiln 25 for combustion of the fuel therein, and the products of combustion from the rotary kiln or clinkering member being delivered therefrom into the calciner above the zone of combustion.

The objects of the present invention are to provide a calciner of the class mentioned, (of the multiple hearth type wherein the hearths are arranged in staggered relation); to provide a lower hearth so arranged or 30 situated relative to its adjacent upper hearth as to give ample proportions or area for complete combustion of the required fuel at a high temperature; to protect the moving parts from destruction by the high 35 temperature of the flame within the combustion chamber of the calciner; to reduce radiation losses from the flame to the outside atmosphere to a minimum; to provide for the passage of hot gases of combustion 40 or gases of any sort from an outside source, upwardly through an annular flue or wall of the calciner surrounding the lowermost or combustion hearth and discharging same over the next hearth above, and so construct the rabble arm working over the 45 lowermost hearth of the series of hearths

as to materially prolong the life and the efficiency thereof.

In order to comprehend the invention reference should be had to the accompanying 50 sheets of drawings, wherein:—

Figure 1 is a broken elevation part sectional view of a multiple hearth type of calciner with my improvements applied thereto.

Figure 2 is a view in elevation of one of the rabble arms situated within the combustion chamber for movement over the lowermost hearth of the calciner.

Figure 3 is a vertical sectional view taken 70 on the line 3—3, Fig. 2 of the drawings and viewed in the direction of the arrow.

Figure 4 is a similar view taken on the line 4—4, Fig. 2 of the drawings and viewed in the direction of the arrow.

Figure 5 is a detailed sectional view illustrating a modified form of burner arrangement for the combustion chamber of the apparatus.

In the drawings the numeral 1 is used 80 to indicate the outer shell or casing of the calciner, and 2 an insulating lining interposed between the inner wall surface of the shell or casing 2 and the refractory lining 3 of the calciner. The hearths arranged in 85 superposed staggered relation are indicated by the numeral 4, which hearths are projected inwardly from the refractory wall lining 3 of the calciner. Through the apparatus is extended a vertically disposed rotating 90 shaft or column 5 which is supported and driven by mechanism not shown but of the usual type for imparting rotary movement to said column, which central column supports and carries the rabble arms 6 radially projected therefrom to overlie the hearths 4 of the calciner. The arrangement and disposition of the hearths 4 and equally so the rabble arms 6 conform to arrangement and construction as in the calcining 100 apparatus set forth and described in my said pending application No. 572,895 and call for no specific description herein, the said rabble arms being of the hollow type and air being received therein from the 105 rotating hollow column 5 and circulating therethrough for cooling purposes. Like in the calciner of my said pending application the hollow rotating column 5 is protected from the effect of the high temperature of 110 the atmosphere passing upwardly through the calciner by means of the refractory lin-

ing 7. The lowermost series of rabble arms 8 of the calciner, which are situated to move over the lowermost hearth 9 of the calciner as to construction correspond with the rabble arms 6 which move over the upper series of hearths 4, but instead of providing the said rabble arms with the downwardly projected rabble teeth 10 of the rabble arms 6, there is provided a plow shaped covering 11, for each of the rabble arms 8, the said plow shaped covering or tooth 11 being constructed to slip over the said rabble arms 8, the bottom portion of the rabble arm being preferably protected by a bottom piece 14 which fits within guideways 13 formed in the lower walls of the plow shaped rabble tooth 11, and the said rabble tooth and plate 14 are held to the rabble arm by means of a bolt 15, which passes through a web 15' extended from the rabble arm: Figs. 3 and 4 of the drawings. The plow-like rabble tooth or covering 11 for each rabble arm 8 is preferably formed of hard burnt fire clay or porcelain and serve to protect the rabble arms 8 from the effect of the high temperature within the combustion chamber 16 of the calciner and by so doing prolong the life and efficiency of the said rabble arms 8. Each plow-like rabble tooth 12 is provided with a toe extension 17 and a sloping face 18, which said toe 17 during the horizontal movement of the rabble arms 8 over the surface of the hearth 9 moves almost entirely below the material being treated and delivered thereon from the adjacent upper hearth 4 of the apparatus and by the action thereof the material is lifted by the toe extension 17 and dropped off the rear of the rabble tooth with a component of movement outward along the said rabble arm, due to the slope of the face 18. Each of the rabble arms 8 is provided with an end member 19 which serves the function of a pusher and carries the calcined material which has reached the outside of the hearth 9 around to the discharge outlet opening 19' of the calciner and through which the calcined material is discharged.

Surrounding the lowermost hearth 9 of the calciner is an annular vertically extended flue 20, which flue, where the calciner is utilized in conjunction with a clinkering apparatus, is usually supplied with hot gases of combustion from the said clinkering member, the same being delivered into the annular flue 20 through a suitable passageway 21. These gases of combustion delivered into the annular flue 20 pass upwardly and absorb heat from the flame within the combustion chamber 16, which passes through and is radiated from the refractory lining 22, and pass upwardly and are delivered into the calciner at a point above the lowermost hearth of the series of hearths 4 of the apparatus.

A port 23 is provided through the wall of the combustion chamber 16, said port preferably being arranged semi-tangentially with reference to the circumference of the calciner and through which port is admitted pulverized, atomized, or gaseous fuel by means of any suitable type of burner; and through the wall of the combustion chamber is formed a port 24 for admitting air for combustion, which port is arranged semi-tangentially in direction and situated immediately beneath the fuel port 23. The air for supporting combustion is usually preheated and conveyed by a suitable duct 25 from the cooling element of the apparatus when the same is utilized in combination with the clinkering and cooling element of a combined apparatus, or when these elements are omitted the air is taken through the duct 25 from any suitable source of supply.

Except for the provision of the large combustion chamber between the lowermost hearth of the calciner and the upper hearth adjacent thereto, the providing of means for the utilization of flames of high thermal intensity within the said combustion chamber and so protecting the rabble arms working over the lowermost hearth of the calciner as to enable the same to withstand the flames of high thermal intensity, the calciner is the same as to structural arrangement and the path of travel of the material to be calcined therethrough and subjecting the same to the ascending stream of heated gas, as is the construction of the calcining element of the apparatus set forth and described in my before-mentioned pending application No. 572,895. While I have illustrated and described the preferred manner of introducing the fuel within the combustion chamber and for admitting air therethrough for supporting proper combustion, it will be understood that any other suitable arrangement of means for introducing an intense form of combustion may be utilized, and, instead of the form and disposition of the heating and air supplying means previously described, there may be, when a more intense form of combustion is desired, the arrangement of burner and air port illustrated in Fig. 5 of the drawings, in which 26 designates a water cooled tuyere or burner inserted in the path of the incoming air for liberating the fuel at the proper point and at the required velocity for making a highly intense flame which issues from the port 24' over the material being treated.

When the calciner is to be employed independently of association with a clinkering apparatus and is to be employed merely for the purpose of simply calcining such material as lime rock or magnesite, then and in such case the calcined material dropping through or discharged from the port 130

will be conducted over a series of cooling hearths, not shown but formed integral with the furnace structure and the cooling air permitted to pass over these hearths will be sealed from passing upwardly through the discharge outlet 19' but will be conveyed to the passage or duct 25 and delivered as preheated air from the uppermost cooling hearth and over the lowermost hearth of the calcining apparatus.

By means of the above described invention there is provided a calciner wherein it is possible to use flames of high thermal intensity or power in the interior of a calciner of the multiple hearth type and in direct contact with the material under treatment without injury to the metal parts of the apparatus and without incurring undue heat losses to the outside. Under the described constructed calciner practically all of the heat of the flames passes to the material under treatment and inasmuch as this heat is of high thermal intensity, the economical and rapid progress of calcination is assured over and above that possible in a calciner of ordinary construction.

The invention has been illustrated in its preferred embodiment, but it will be understood that changes may be made in the details of construction without varying or departing from the nature and spirit of the invention and I wish to be understood as claiming the invention as broadly as the state of the art will permit.

Having thus described my invention what I claim as new and desire to secure by Letters Patent is:

1. A calciner for the described purpose, the same comprising an outer shell, a series of superposed hearths arranged therein in staggered relation, a series of rabble arms associated with and movable over each of said hearths, a rotatable column carrying said arms centrally extended through the shell, a bottom hearth for the shell situated below the lowermost hearth of the series of hearths a distance in excess of the distance between said hearths to provide an enlarged combustion chamber, means for admitting combustible fuel and air for supporting combustion within the said chamber, a series of rabble arms carried by the rotatable column and moveable over the bottom hearth of the calciner for advancing calcined material to a discharge outlet, and a plow-shaped rabble tooth covering for each of the rabble arms associated with the said bottom hearth.

2. A calciner for the described purpose, the same comprising an outer shell provided with an inner insulated protected liner wall, a series of superposed hearths arranged therein in staggered relation, a bottom hearth for the shell situated a distance below the lowermost hearth of the

series of hearths to provide a combustion chamber of enlarged area, rotatable rabble arms associated with each of the hearths for moving material thereover, a plow-shaped rabble tooth covering for each of the rabble arms associated with the bottom hearth of the calciner, and means for admitting combustible fuel and air for supporting combustion within the combustion chamber of the said calciner.

3. In a calciner for the described purpose, the combination with the combustion chamber thereof, of a plurality of rabble arms associated with the hearth of said chamber, means for admitting combustible fuel and air for supporting combustion within the said combustion chamber, and a plow-shaped rabble tooth covering for each of the rabble arms associated with the hearth of said combustion chamber.

4. In a calciner for the described purpose, the combination with the combustion chamber thereof, a plurality of rotatable rabble arms associated with the hearth of said chamber, means for admitting combustible fuel and air for supporting combustion within the said chamber, a plow-shaped rabble tooth covering removably secured to each of the rabble arms situated within the combustion chamber.

5. In a calciner for the described purpose, the combination with the combustion chamber thereof, a bottom hearth for said chamber, a plurality of rabble arms rotatable within the chamber, means for admitting combustible fuel within the said chamber, an annular flue surrounding the hearth of the chamber for admitting air therein for supporting combustion, and a plow-shaped covering removably held to each of the rabble arms associated with the hearth of said chamber.

6. A calciner for the described purpose, the same comprising an outer shell provided with an insulated inner lining wall, a series of superposed hearths arranged within the shell in staggered relation, a plurality of rabble arms associated with each of the said hearths for moving material thereover, means extended centrally within the calciner for supporting and imparting rotary movement to the said rabble arms, a bottom hearth for the calciner situated a distance below the lowermost hearth of the mentioned series a distance in excess of that between the hearths of said series to provide a combustion chamber of enlarged area, means for admitting combustible fuel and air therein within said chamber for supporting combustion, a plurality of rabble arms associated with the hearth of the combustion chamber for advancing calcined material thereover to a discharge outlet, and a removable plow-shaped tooth covering for each of said rabble arms.

7. A calciner for the described purpose, the same comprising an outer shell, a series of superposed hearths arranged therein in staggered relation, a series of rabble arms associated with and movable over each of said hearths, a hollow rotatable column carrying said arms centrally extended through the shell, a bottom hearth for the shell situated below the lowermost hearth of the series of superposed hearths a distance in excess between said hearths to provide an enlarged combustion chamber, means for admitting fuel within the combustion chamber and air therein for supporting combustion, and a series of rabble arms carried by the rotatable column and a plow-shaped rabble tooth covering for each of the said rabble arms, movable over the bottom hearth of the calciner and adapted for working beneath the surface of the material therein under treatment.

8. In a calciner for the described purpose, the combination with the combustion chamber thereof, a bottom hearth for said chamber, a plurality of rabble arms associated with said hearth for movement thereover and adapted for working beneath the surface of material therein for treatment, a removable plow-shaped tooth covering for each of said arms, and means for admitting fuel and air for supporting combustion within the said combustion chamber.

9. In a calciner for the described purpose, the combination with the combustion chamber thereof, a plurality of rotatable rabble arms associated with the hearth of said chamber, means for admitting fuel and air for supporting combustion within the said chamber and a plurality of plow-shaped rabble teeth removably secured to each of the rabble arms situated within the combustion chamber and adapted for working beneath

the surface of the material within said chamber under treatment.

10. In a calciner for the described purpose, the combination with the outer shell thereof, of a series of superposed hearths arranged therein in staggered relation, a bottom hearth for the outer shell situated a distance below the lowermost hearth of the series of hearths to provide a combustion chamber in excess of the distance between the hearths of said series, and a plurality of rabble arms movable over the said respective hearths and adapted to advance material discharging thereon, a removable plow-shaped tooth covering secured to each of the rabble arms adapted for working over the hearth of the combustion chamber, means for admitting fuel within the combustion chamber and air therein to support combustion.

11. A calciner for the described purpose, the same comprising an outer shell provided with an insulated inner lining wall, a series of superposed hearths arranged within the shell in staggered relation, a plurality of rabble arms provided with rabble teeth associated with each of said hearths for advancing material thereover, means for imparting rotary movement to the said rabble arms, a bottom hearth for the calciner situated a distance below the lowermost hearth of the mentioned series, a distance in excess of that between the hearths of said series to provide a combustion chamber of enlarged area, means for admitting fuel and air within the said chamber, and a plurality of rabble arms each provided with a removable plow-shaped tooth covering associated with the hearth of the combustion chamber for advancing material thereover to a discharge outlet.

In testimony whereof I have signed my name to this specification.

ROBERT D. PIKE.
